ELECTRONIC DRYING OF FOOTS

Benjamin Clayton, Houston, Tex., assignor, by
mesne assignments, to Benjamin Clayton,
Houston, Tex., doing business as Refining, Un-
incorporated

Application October 19, 1943, Serial No. 506,899

6 Claims. (Cl. 260—412.5)

1

This invention relates to a drying process and particularly to a process of drying thick, viscous organic materials such as the gums or soapstock separated from glyceride oils during partial or complete refining steps, the drying operation being carried out by employing high frequency electric fields.

The gums separated from glyceride oils, such as vegetable oils, in a partial refining or gum precipitating and separating step are usually in the form of a thick, viscous, gummy material which contains on the average between 35 and 50% water. These gums particularly from vegetable oils are valuable by-products of a refining operation as they have a high phosphatide content and contain other valuable materials. In order to render them stable against fermentation or bacterial growth to produce a phosphatidic material useful for many purposes, or to condition them for solvent purification steps to recover purified phosphatides and other valuable materials, the gums must have substantially all of their contained water removed. The phosphatides are deleteriously affected by high temperatures and as the gums are very poor conductors of heat, it has been found extremely difficult to dry these materials without thermal degradation thereof. The only practical process thus far developed has been the stirring of batches of the viscous material in vacuum chambers with the application of moderate heat through the walls of the container. This requires large amounts of power and long periods of time, usually many hours or days, as only moderate heat can be employed and the water or moisture contained in the gums is liberated slowly.

Also, the soapstock from alkali refining of glyceride oils, such as animal and vegetable oils, contains many valuable ingredients including neutral oil, soap, phosphatides, unsaponifiables, such as sterols, sterol glycosides, etc. This soapstock contains relatively large amounts of phosphatides if no prior partial refining operation has been carried out, which is probably the case in the majority of refining operations. A large portion of these phosphatides, as well as neutral oil, are recoverable in undecomposed form by solvent treatments if such treatment is carried out promptly after the soapstock is separated from the oil. Such recovery operations desirably include a drying step in order to condition the soapstock for solvent treatment. Even if no solvent treatment of the soapstock is contemplated, drying of the soapstock is desirable in order to prevent bacterial growth therein and the dried soapstock is a valuable detergent material. Again, the

2

5 soapstock is a viscous, gummy material in which the more valuable ingredients are damaged by high temperatures. The soapstock is also a very poor conductor of heat and no practical process has been worked out for the large scale drying of soapstock at low temperatures so as to not damage the heat-sensitive materials contained therein.

In accordance with the present invention, the 10 soapstock from either a partial refining operation or an alkali refining operation are spread in a layer upon a supporting surface and while in this form are subjected to the action of a high frequency alternating field. By this operation heat is generated within the body of the film and water can be rapidly evaporated without increasing the 15 temperature of the materials being treated to that which will damage the thermo-sensitive materials and without the necessity of transmitting the heat from the exterior of the material through the material itself into the interior thereof. Attempts to rapidly dry these materials even in thin films by the application of heat thereto through heated surfaces has not been productive 20 of practical results as overheating and destruction of valuable constituents has resulted.

It is, therefore, an object of the present invention to provide an improved process for drying 25 foots separated from glyceride oils during partial or complete refining operations.

Another object of the invention is to provide 30 an improved process of drying gums separated from glyceride oils during a gum precipitating and separating operation in order to quickly remove the water therefrom without thermal 35 decomposition of the valuable materials contained therein.

Another object of the invention is to provide 40 an improved process of drying soapstock from the alkali refining of glyceride oils without thermal destruction of the valuable constituents thereof.

Another object of the invention is to provide 45 an improved process of drying at low temperatures, thick, viscous, gummy organic materials containing water.

Another object of the invention is to provide 50 a process of drying thick, viscous, gummy organic materials containing water, by subjecting such materials in a thin film to a high frequency alternating field and liberating from the material water vapors generated in the material.

Another object of the invention is to provide 55 an apparatus for subjecting films of thick, viscous, gummy organic material to the action of a high frequency alternating field.

A still further object of the invention is to provide an apparatus for removing water from thick, viscous organic materials by subjecting such materials while in a thin film, to a high frequency alternating field under vacuum conditions.

Other objects and advantages of the invention will appear in the following description of preferred embodiments thereof given in connection with the attached drawing of which

Fig. 1 is a somewhat diagrammatic vertical section through an apparatus in accordance with the present invention;

Fig. 2 is a vertical section through the apparatus of Fig. 1 taken on the line 2—2 of Fig. 1;

Fig. 3 is a view similar to Fig. 1 of a modified form of apparatus, and

Fig. 4 is a vertical section taken on the line 4—4 of Fig. 3.

The apparatus of Figs. 1 and 2 may include a gas-tight casing 10 which is preferably of cylindrical form made up of cylindrical side wall 11 and end walls 12 and 13 suitably secured thereto. A shaft 14 may be journalled in bearings 16 and 17 secured to the end walls 12 and 13, respectively, one end of the shaft 18 extending through a packing gland 19 secured to the bearing 16 so as to seal the casing 10 against entrance of air. The shaft 14 may support a drum 21 having a peripheral surface 15 and may also have a pulley 22 secured to its end 18 for rotation of the shaft 14 and drum 21.

The material operated upon by the present invention is, in general, sufficiently fluid to be pumped but will not flow freely through pipes or over a surface in a film or layer. This material may be pumped through a pipe 23 into a supplemental casing 24 having side walls 26 and 27 and end walls 28 and 29 suitably secured to the side wall 11 of the main casing 10. The side wall 26 terminates short of the surface of the drum 21 and may have a sliding plate 31 secured thereto for adjustment toward and away from the surface of the drum 21. The walls 27, 28 and 29 closely engage the surface 15 of the drum 21, whereas the inner end of the sliding plate 31 is spaced slightly from the surface of the drum 21 so that rotation of the drum 21 in the direction of the arrow 33 causes a layer of material to be formed on and be carried by the said surface 15 of the drum.

An electrode 34 is suitably supported concentric with the drum 21 by suitable insulating supports 36, 37 and 38, the insulating support 37 having a conductor 39 extending therethrough for connection to one terminal of a high frequency generator 41, the other terminal of the high frequency generator being connected to the casing 10 and through the shaft 14 to the drum 21. The layer of the material to be treated on the drum 21 is carried through the space between the electrode 34 and the drum 21 and a high frequency alternating field is produced in said space through the film of material by the high frequency generator 41. The electrical characteristics of the material being treated are such that the water contained therein is selectively heated and heat is generated internally of the layer so that it is not necessary to supply heat to the interior of the layer from a heated surface, the drum 21 and the electrode 34 remaining relatively cool. Preferably a vacuum is maintained in the casing 10 by withdrawal of vapors through the pipe 42 which may be connected to any suitable type of vacuum and condensing system (not shown). Vapors generated by the heat due to the electrostatic field

are rapidly liberated from the film of the material on the drum 21 and withdrawn through the pipe 42.

The drum 21 is rotated at a rate so that the material is substantially completely dried before leaving the space between the electrode 34 and the drum 21 and drops from or may be scraped from the surface of the drum 21 by means of a scraper 43. The dried material falls into an axially extending opening 44 in the bottom of the casing 10 and is received in the housing 46 of a screw conveyor 47 secured to the casing 10. The screw conveyor 47 is preferably of the sealing type provided with a shaft 48 which terminates in an enlarged portion 49 at its discharge end. The dried material, which is, in general, still plastic, is compressed into a thin layer in the space between the enlarged end 49 of the shaft and the conveyor casing 46 so as to seal the conveyor against entrance of air and provide for removal of the material from the casing without breaking the vacuum therein.

The modified apparatus shown in Figs. 3 and 4 also includes a gas-tight casing 50 formed of a central cylindrical portion 51 and two end members 52 and 53. A conveyor, including a flexible member 54 and a pair of rollers 56 and 57 are mounted within the casing 51 so that the flexible member 54 extends longitudinally of the casing and has its upper run 58 positioned adjacent an electrode 59 in the form of a conducting plate, such as a metal plate, suitably supported by insulating members 61, 62 and 63 from the casing 51, the insulating member 62 having a conductor 64 extending therethrough and connected to one terminal of a high frequency generator 66, the other terminal of which is connected to the casing 50.

The material to be treated is delivered into the casing 50 through an auxiliary chamber formed in a casing 67. A pipe 68 feeds the auxiliary casing 67 which is shown as a part of the end member 52. The auxiliary casing 67 has its bottom portion provided with a plurality of vertically extending holes 69 forming extrusion nozzles for the extrusion of strings of the material upon the upper surface of the upper run 58 of the conveyor 54. To assist in uniformly distributing the material through the nozzles 69 a rotating agitator having arms 71 may be mounted in the auxiliary casing 67 concentric with the lower semi-cylindrical surface 72 of the casing 67. By pumping the material to be treated under pressure into the casing 67 through the pipe 68, thin strings of the material to be treated are uniformly extruded by conjoint action of the pump pressure and the agitator arms 71 and these strings are laid on the upper run 58 of the conveyor 54 and carried longitudinally thereof through the space between said upper run and the electrode 59.

The high frequency generator 66 produces a high frequency electrostatic field in the said space threading the strings of the material on the conveyor 58, which is of conducting material such as a metal band or screen. The water in the material is rapidly heated by heat generated throughout the layer of material and water vapor is produced and liberated from the layer through the upper exposed surface thereof. Preferably the vapors are withdrawn from the casing 51 through a pipe 72 connected to any suitable condensing and vacuum system (not shown). By the conjoint use of the electrostatic field and vacuum the material being treated is rapidly dried at low

temperatures. The dried material falls from the discharge end of the conveyor 54 into an opening 73 in the cylindrical portion of the casing 51, any material tending to adhere to the band 54 being removed therefrom by a scraper 74. As described with considerable detail relative to Figs. 1 and 2, a screw conveyor housing 46 having a screw conveyor 47 therein may be employed to discharge dried material from the housing 51 without breaking the vacuum in the housing 51. The screw conveyor in the casing 46 may be driven from any suitable source of power through the gear or pulley 75. The band or endless conveyor 54 may be driven by means of a shaft 76 supporting the pulley 56 and having one end extending from the housing 51 through a bearing 71 and driven from any suitable source of power through the pulley 78. Also the agitator 71 may have its shaft 79 extend through one end of the casing so as to be driven by a pulley or sprocket 81 from any suitable source of power. It will, of course, be apparent that the material feeding means of Figs. 1 and 2 can be adapted to the apparatus of Figs. 3 and 4 and that the material feeding means of Figs. 3 and 4 can be employed in the apparatus of Figs. 1 and 2.

By treating gums, soapstock, or other similar viscous, gummy, organic material containing water in a layer or thin film carried by a moving supporting surface, by an electrostatic field in accordance with the present invention, the water may be substantially completely and rapidly removed from the material at low temperatures. No thermal destruction of heat-sensitive materials takes place during the drying operation and the material may be rapidly and quickly dried in a continuous manner as it is received from prior process steps and before chemical reactions or bacterial action have time to go forward. This is of particular importance with respect to gums from partial refining operations and soapstocks from alkali refining operations on glyceride oils. If any of these materials are allowed to stand, they ferment and become putrid resulting in destruction of valuable materials. Furthermore, phosphatides, as well as valuable neutral oil, in soapstock from alkali refining operations are also saponified by excess alkali upon standing to produce less valuable soap and the drying operation of the present invention accomplishes the drying operation before this saponification can take place. While operations under vacuum conditions are preferred, since vapors are much more rapidly generated and liberated from films or layers of the material being treated and the average temperature of the material may be very much reduced over operations at atmospheric pressure, it is apparent that the air-tight casings described in detail above may be eliminated or opened and the remaining apparatus employed at atmospheric pressure if desired. In general, however, operations under vacuum condition produces very much improved results. The frequency of the voltage supplied by the high frequency generators will vary with the material being treated as well as the apparatus employed but will usually range between 10 and 40 megacycles, although radio frequencies between 1 and 100 megacycles are within the contemplation of the present invention.

While I have disclosed the preferred embodiments of my invention it is understood that the details thereof may be varied without departing from the essence of the invention.

I claim:

1. The process of drying foots from the refining of glyceride oils, said foots being a thick viscous organic material containing gums and also containing water dispersed therein, which process comprises, spreading said foots in a thin layer upon a supporting surface, moving said surface having said layer thereon through a drying zone, subjecting said layer while in said zone to the action of a radio frequency alternating electric field of sufficient intensity to generate heat in said foots and vaporize said water, maintaining a surface of said layer exposed to a vapor liberating space in said zone to provide for free escape of water vapor from said foots, withdrawing water vapor from said zone at a rate sufficient to produce a vacuum in said zone, and removing the resulting dried foots from said supporting surface and from said zone.
2. The process of drying foots from the refining of glyceride oils, said foots being a thick viscous organic material containing gums and also containing water dispersed therein, which process comprises, spreading said foots in a thin layer upon a supporting surface by extruding upon said surface a plurality of parallel strings of said foots, moving said surface having said layer thereon through a drying zone, subjecting said layer while in said zone to the action of a radio frequency alternating electric field of sufficient intensity to generate heat in said foots and vaporize said water, maintaining a surface of said layer exposed to a vapor liberating space in said zone to provide for free escape of water vapor from said foots, withdrawing water vapor from said zone at a rate sufficient to produce a vacuum in said zone, and removing the resulting dried foots from said supporting surface and from said zone.
3. The process of drying gums from the refining of glyceride oils, said gums being a thick viscous organic material containing water dispersed therein, which process comprises, spreading said gums in a thin layer upon a supporting surface, moving said surface having said layer thereon through a drying zone, subjecting said layer while in said zone to the action of a radio frequency alternating electric field of sufficient intensity to generate heat in said gums and vaporize said water, maintaining a surface of said layer exposed to a vapor liberating space in said zone to provide for free escape of water vapor from said gums, withdrawing water vapor from said zone at a rate sufficient to produce a vacuum in said zone, and removing the resulting dried gums from said supporting surface and from said zone.
4. The process of drying gums from the refining of glyceride oils, said gums being a thick viscous organic material containing water dispersed therein, which process comprises, spreading said gums in a thin layer upon a supporting surface by extruding upon said surface a plurality of parallel strings of said gums, moving said surface having said layer thereon through a drying zone, subjecting said layer while in said zone to the action of a radio frequency alternating electric field of sufficient intensity to generate heat in said gums and vaporize said water, maintaining a surface of said layer exposed to a vapor liberating space in said zone to provide for free escape of water vapor from said gums, withdrawing water vapor from said zone at a rate sufficient to produce a vacuum in said zone, and

removing the resulting dried gums from said supporting surface and from said zone.

5. The process of drying soapstock from the refining of glyceride oils, said soapstock being a thick viscous organic material containing gums and also containing water dispersed therein, which process comprises, spreading said soapstock in a thin layer upon a supporting surface, moving said surface having said layer thereon through a drying zone, subjecting said layer while in said zone to the action of a radio frequency alternating electric field of sufficient intensity to generate heat in said soapstock and vaporize said water, maintaining a surface of said layer exposed to a vapor liberating space in said zone to provide for free escape of water vapor from said soapstock, withdrawing water vapor from said zone at a rate sufficient to produce a vacuum in said zone, and removing the resulting dried soapstock from said supporting surface and from said zone.

6. The process of drying soapstock from the refining of glyceride oils, said soapstock being a thick viscous organic material containing gums and also containing water dispersed therein, which process comprises, spreading said soapstock in a thin layer upon a supporting surface by extruding upon said surface a plurality of parallel strings of said soapstock, moving said surface having said layer thereon through a drying zone, subjecting said layer while in said zone to the action of a radio frequency alternating electric field of sufficient intensity to generate

heat in said soapstock and vaporize said water, maintaining a surface of said layer exposed to a vapor liberating space in said zone to provide for free escape of water vapor from said soapstock, withdrawing water vapor from said zone at a rate sufficient to produce a vacuum in said zone, and removing the resulting dried soapstock from said supporting surface and from said zone.

BENJAMIN CLAYTON.
